US00D831706S

(12) **United States Design Patent** (10) Patent No.: **US D831,706 S**
(45) Date of Patent: **** Oct. 23, 2018**

(54) **SPOOL HOLDER**

(71) Applicant: **Andres Perez**, Miami, FL (US)

(72) Inventor: **Andres Perez**, Miami, FL (US)

(**) Term: **15 Years**

(21) Appl. No.: **29/620,206**

(22) Filed: **Aug. 16, 2016**

(51) LOC (11) Cl. **15-06**

(52) U.S. Cl.

USPC **D15/78**

(58) **Field of Classification Search**

USPC **D15/66-78; D3/18-25**

CPC **B65H 49/00-54/88**

See application file for complete search history.
